MOUNTING ENCLOSURE FOR LIGHTING FIXTURES

Simon Deutsch and Roland A. Manning, Sheboygan, Wis., assignors to Moe-Bridges Corporation, Sheboygan, Wis., a corporation of Wisconsin

Application August 23, 1948, Serial No. 45,632

6 Claims. (Cl. 240—2)

1

This invention relates to a mounting enclosure for lighting pictures and component parts thereof and more particularly to a decorative lighting installation which presents to the observer a continuous line of light generated by either a single lamp or a plurality of lamps mounted behind a decorative valance. The invention while not limited thereto affords a unitary installation comprising a single or a plurality of linearly aligned self-contained lamp fixtures for producing a substantially even light distribution along the length of the installation, the light source being mounted behind the valance.

The invention more especially contemplates installations comprising a plurality of aligned fluorescent or other types of tubular lamps or a combination of tubular and other types of lamps or finally only lamps other than the tubular type. The invention affords not only an aligned support for a plurality of lamps and lamp fixtures, but also an ornamental valance which shields the lamps to any desired degree and which enhances the decorative effect of the installation.

In carrying out the invention, we provide a valance assembly comprising component elements which not only afford a valance assembly but also the mounting of the valance from a supporting wall and the mounting of one or a plurality of lighting fixtures on certain of said component elements.

The invention is particularly advantageous for mounting a plurality of axially aligned lamp fixtures for tubular fluorescent lamps, such as disclosed in our copending application Serial Number 681,472, filed July 5, 1946. Said application discloses a fluorescent light fixture which affords "in-line end-to-end" installation of a plurality of fixtures, whereby direct connections of a supply circuit is made to one of the fixtures, while the other fixtures are electrically connected in parallel to the first fixture by cooperating circuit connector elements at the ends of the respective fixtures. Furthermore, said lamp fixtures are adapted to afford support for shields or valances individual to each fixture, but giving the appearance of a single unitary structure when a plurality of fixtures are assembled as aforesaid. The present invention affords a more flexible "in-line" installation whereby the lamps or fixtures may be separated from each other laterally, but shielded by the valance in such a manner that they present collectively a unitary light source as will appear hereafter.

An object of the invention is to provide for a lighting installation a plurality of different

2

structural elements which may be assembled in a variety of ways to provide a corresponding decorative lighting installation.

Another object is to make certain of the aforementioned elements interchangeable so as to afford different assemblies of lighting installations.

Another object is to provide a lighting system which can readily be changed or extended after initial installation thereof.

Another object is to provide a lighting system which by proper selection of the various structural elements can readily be assembled so as to afford any one of a number of lighting effects.

Another object is to provide an installation which requires a minimum of fixed wiring, while affording the possibility of rearrangement and extension without any change in such fixed wiring.

20 Other objects and advantages will appear from the following description.

The accompanying drawings are illustrative of various components and various modes of assembly thereof to form a complete lighting installation embodying the present invention. In the drawings,

Fig. 1 is a schematic perspective of two tubular lighting fixtures assembled on supporting brackets in accordance with the invention,

30 Fig. 2 is a front elevation of the assembly shown in Fig. 1, with the addition of front and end decorative parts of a valance.

Fig. 3 is a top view of the assembly in Fig. 2.

Fig. 4 is a perspective of an end mounting bracket of the assembly shown in Figs. 1 to 3.

Fig. 5 is a perspective of a partial assembly, including an intermediate mounting bracket of the assembly shown in Figs. 1, 2 and 3.

Fig. 6 is a fragmentary rear view of a pair of axially aligned tubular lamp lighting fixtures in close juxtaposition to each other.

Fig. 7 is a perspective of a supporting element for the valance, which may be substituted for that shown in Fig. 5.

45 Fig. 8 is an end view of a complete assembly, as shown in Fig. 2, and

Fig. 9 is a section along line 9—9 of Fig. 3.

Referring to the drawings (Figs. 1 to 3 and 9) the same illustrates an assembly for two fluorescent lamp fixtures 10, in accordance with our invention. Each of said fixtures comprises the usual base housing 11, which contains the necessary auxiliaries for connecting the lamp into circuit. The base is provided with sockets 12 for the support of a fluorescent tube. Each

unit is also provided at opposite ends with a pair of male terminals 13 and female terminals 14, respectively, by means of which the unit may be connected to a supply circuit and the several units may also be connected in parallel with each other to said circuit in accordance with the disclosure in the aforementioned application. However, other suitable types of fluorescent lamp fixtures may be employed in connection with the present invention as will appear hereinafter.

The two fixtures are supported near their respective ends by channel shaped sheet metal brackets 15, shown more in detail in Figs. 4 and 5. The central web of the bracket is provided with suitable slots 16 for the passage of screws by means of which it may be attached to a supporting surface. The side walls of the bracket are provided with elongated slots 17 for the passage of screws 18 in the fixture 10, for attachment of the fixture to the bracket. The bracket 15 is of such transverse dimension that it embraces the housing 11 and of such lengths as to afford the mounting of two fixtures in alignment and in close juxtaposition with or spaced apart a longitudinally adjustable distance from each other. In the latter event a flexible cord connector 19 (shown in dotted lines, Fig. 2) provided with male and female ends, respectively, is interposed between the female and male terminals of the unit. The brackets 15 which are employed at the outer ends of the assembly may have attached thereto end frames 20 which are generally of rectangular shape and which are provided with an upturned top flange 21, a front flange 22, a channel like bottom flange 23, and an angle bracket 24, riveted or welded to the end panel 20. The end frames 20 are made in two symmetrical forms, for right and left hand mounting, as will be apparent from the drawing. The frame 20 when attached to the bracket 15 depends below the latter and is attached thereto by screws or rivets passing through the flange 21 and the angle bracket 24. The ends of the flange 22 have cut therein slots 25 for the passage therethrough of angular supporting clips 26 and 27, respectively, arranged for sliding engagement therein. The clips 26 and 27 may be secured to the frame 20 by means of screws 28 which pass through slots 29 in the frame 20, thus permitting their adjustment relative to the flange 22.

Adjustably attached to the center bracket 15 (Fig. 5) by means of a screw 31 is a strap 30 to which in turn is attached a generally U-shaped shield support 35. Fastened to the upper edge of the 35 is a strap 32, which is adapted to register with the strap 30 and which may be adjustably fastened thereto by means of a screw 33 passing through an adjusting slot 34 in the strap 32. By this arrangement it is possible to adjust the distance of the shield support 35 relative to the wall surface to which the bracket 15 is attached. The center shield support 35 is provided at its upper and lower edges with struck up finger like projections 36, the purpose of which will be explained. The end frames 20 may be provided with corresponding projections 37. Suitable decorative end panels 38 may be inserted between the projections 37 of the end frames 20 and decorative front panels or valances 39, which may be transparent or translucent, may be supported on the support 35 by the inturned bracket and spring clips 40 and 41, and the clips 26 and 27, respectively, to extend longitudinally between corresponding brackets and in front of the lamps. In that

event an additional decorative panel 42 may be mounted between the finger like projections 36 in front of the shield support 35.

Instead of using the intermediate shield support 35, it is also possible to attach only the strap 30 directly to the brackets 15 (Fig. 7) and provide this strap with a downward projection 43 to which a decorative panel or the like 44 (shown in dotted lines) may be attached. The strap 30, however, may be entirely omitted if an intermediate support of panel 44 is not desired.

The intermediate bracket 15 and panel 42 may be entirely omitted in which case the decorative front panel or valance 39 extends as a single unit 15 between the two end panels (not shown).

If the installation is below the line of vision it may be desirable to cover the space above the light source with a decorative shield 50 (Fig. 9 and also in dotted lines Figs. 3 and 8). To support the shield 50, a Z-shaped bracket 51 may be welded or otherwise fastened to the upper flange 21 of the end frames 20. The shield 50 is thus secured against lengthwise movement, while if desired means may be provided to secure it 25 against crosswise movement.

It will be apparent that the intermediate and end brackets afford considerable adjustment in the length of the individual unit so that the longitudinal distance between lamps may be varied 30 over a wide range by virtue of the shielding panels or valance the installation affords a unitary and pleasing appearance and the light which is radiated by the unit is evenly distributed, thus affording a great flexibility in installation.

As aforesaid the panels 39 may be made of transparent or translucent material thus permitting some light to pass through them. When provided with decorative designs the artistic effect of the installation will be enhanced. They may 40 also be made of a thin piece of wood, metal or cardboard and covered with a fabric or other material which matches the interior of the room in which they are used. Similar arrangements are possible with respect to the end panels 38.

While the invention has been illustrated and described in connection with tubular lamps arranged end to end, it will be apparent that it may also be used in connection with incandescent or other lamps of various shapes which are supported on the valance supports, rather than independent thereof. Similarly, instead of employing the combined unitary fluorescent fixtures arranged in tandem circuit, independent fixtures including their supports and necessary ballast and regulating devices with separate supply wires may be employed. Other modifications within the scope of the appended claims will be apparent to those skilled in the art.

What we claim as new and desire to secure by Letters Patent is:

1. A decorative lighting installation adapted to employ one or more tubular light sources, comprising at least one generally tubular lighting fixture, a plurality of channel-shaped supporting brackets therefor having their sides spaced to receive said fixture, there being at least a bracket at an end of the installation, an end frame for said end bracket and extending transversely thereof and outwardly therefrom to beyond the light source, a valance partially supported by said end frame, and means for supporting the opposite end of said valance independently of said end frame.

2. A decorative lighting installation adapted 75 to employ one or more tubular light sources, com-

prising at least one generally tubular lighting fixture, a plurality of channel-shaped supporting brackets therefor having their sides spaced to receive said fixture, there being at least one bracket at each end of the installation, an end frame for each of said end brackets and extending transversely thereof and outwardly therefrom to beyond the light source, and a valance at least partially supported by said end frames.

3. A decorative lighting installation adapted to employ one or more tubular light sources, comprising at least one generally tubular lighting fixture, a plurality of channel-shaped supporting brackets therefor having their sides spaced to receive said fixture, there being at least one bracket at each end of the installation and an intermediate bracket, an end frame for each of said end brackets and extending transversely thereof and outwardly therefrom to beyond the light source, a longitudinally disposed frame carried by said intermediate bracket spaced from and substantially parallel to said light source on the side thereof opposite said intermediate bracket and toward which said end frames extend, and a valance carried by said frames.

4. A decorative lighting installation adapted to employ one or more tubular light sources, comprising at least one generally tubular lighting fixture, a plurality of channel-shaped supporting brackets therefor having their sides spaced to receive said fixture, there being at least one bracket at each end of the installation and an intermediate bracket, an end frame for each of said end brackets and extending transversely thereof and outwardly therefrom to beyond the light source, a longitudinally disposed frame carried by said intermediate bracket spaced from and substantially parallel to said light source on the side thereof opposite said intermediate bracket and toward which said end frames extend, and a valance carried by said frames, said valance including an end member carried by each of said end frames and at least one longitudinal member disposed between said end frames.

5. In a decorative lighting installation having a plurality of elongated lighting fixtures substantially in longitudinal alignment with each other, a channel-shaped supporting bracket having its sides spaced for receiving the adjacent ends of said fixtures so as to bridge and secure them together, an arm secured to said bracket and extending transversely to the longitudinal axes of said fixtures towards and beyond the open side of said channel-shaped bracket, a longitudinally disposed frame secured to said arm and spaced laterally from said fixture and substantially parallel with the said axes, and a valance supported by said frame and extending lengthwise of said fixtures.
- 10 6. In a decorative lighting installation having a plurality of elongated lighting fixtures substantially in longitudinal alignment with each other, a channel-shaped supporting bracket having its sides spaced for receiving the adjacent ends of said fixtures so as to bridge and secure them together, an arm secured to one of the sides of said bracket and extending transversely to the longitudinal axes of said fixture towards and beyond the open side of said channel-shaped bracket and having its one end turned substantially parallel to the base of said bracket, and a valance supported by the turned end of the said arm and extending lengthwise of said fixtures.
